ELECTRIC WELDING TORCH

Clarence Ivens Barclift, Daytona Beach, Fla.

Application April 9, 1940, Serial No. 328,769

6 Claims. (Cl. 219—8)

This invention relates to an electric welding apparatus and particularly to a manually controlled arc welding torch which is simple in construction and in which the parts are so positioned and arranged as to permit easy manipulation of the torch and afford protection against breaking or injury of the parts during use.

The invention is illustrated in the accompanying drawing forming a part hereof, and in which:

Figure 1 is a side view or elevation of my torch;

Figure 2 is a top or plan view of the same;

Figure 3 is a longitudinal section substantially on the line 3—3 of Figure 2; and

Figures 4 and 5 are respectively transverse sections on the lines 4—4 and 5—5 of Figure 1.

Referring to the drawing in detail, my torch comprises a handle 10 preferably made of wood or other suitable insulating material, and being of sufficient size to afford a firm grip for the hand of the operator. Two bars or conductors 11 and 12 preferably of tubular shape extend longitudinally in the handle 10, and at their outer ends they support the usual carbon electrodes 11E and 12E. The bars 11 and 12 are arranged substantially parallel and are mounted respectively in holes or openings 11A and 12A formed in the handle. The bar 11 is rigidly secured in the handle in any suitable manner as by screws 11B, 11C. An electrical terminal indicated at 13 extends into and is detachably secured to the bar 11 by the screw 11C. The bar 11 is thus mechanically and electrically connected to the terminal 13.

The bar 12 is movably or slidably mounted in the opening 12A of the handle and, as shown particularly in Figure 3, this opening is enlarged or counterbored throughout a portion of its length as indicated at 12B and a coiled spring 14 surrounding the bar 12 is mounted in said enlarged area 12B of the opening. An electrical terminal 15 is connected to the bar 12, said terminal being provided on its end with an enlarged nipple 16 having a threaded end 16A which may be screwed into a threaded socket in the end of the bar 12. In this manner a firm electrical and mechanical connection is made between the bar 12 and terminal 15. The spring 14 bears at one end against a shoulder 12C formed by the enlarged portion 12B of the opening and at its other end against the nipple 16 of the terminal 15. The spring 14 is normally under compression and therefore tends to force the bar 12 and

connected parts toward the right as seen in the drawing.

For manipulating the slidable bar 12 a bell-crank lever 20 is pivotally mounted on a plate 5 21 secured to the handle 10, the lever having at one end a thumb piece 20A arranged in convenient position for engagement by the thumb of the operator and having its other end 20B pivotally connected to a threaded push rod 22 10 which extends through an arm 23 projecting from the slidable bar 12. A lug or projection 20C formed on the lever 20 is adapted to engage the end of the handle 10 to thereby limit movement of the lever 20 about its pivot. A block of 15 insulating material 24 is firmly mounted in the opening in the arm 23 and the rod 22 passes through this block. An adjusting nut 25 is threaded onto the rod 22 and this nut is adapted to contact with the block 24 and thus form an 20 adjustable stop to limit inward movement of the slidable bar 12 under the action of the spring 14. The block 24 is yieldably held against the nut 25 by the spring 14, and the nut thus affords means 25 by which the movable electrode 12E can be given a permanent adjustment or setting relative to the other electrode.

From the foregoing, it will be seen that by 30 moving the thumb piece 20A upwardly the movable electrode 12E may be brought into contact with the electrode 11E to strike the arc. Then by permitting the thumb piece to move downwardly, the electrode 12E will be moved away from the other electrode under the action of the spring 14. The arrangement is such as to afford 35 smooth and easy operation of the lever 20 so that the electrodes can be readily moved and held in position to produce the character of flame desired.

To assist in holding the conducting bars 11 and 40 12 properly spaced and in alignment with the openings in the handle 10, a block 26 of suitable insulating material is mounted on said bars, being slidable on the bar 11 and rigidly secured to the bar 12 by a set screw 26A.

45 To support the electrodes and permit the same to be adjusted as they gradually burn away, each of the conducting bars 11 and 12 is provided at its outer end with a rigid holder 27 having a transverse channel or groove, preferably U-shaped, for receiving a carbon electrode, the holders 27 being arranged at such an angle as to give the electrodes the proper angular relation to each other. A movable clamp 28 is pivotally mounted adjacent the outer end of each of the bars 11 and 12, and the inner ends of such clamps

are yieldably pressed toward the holders 27 by small springs 28, so that the electrodes are yieldably held in position. Slight pressure on the inner ends of these clamps will depress the springs 28 and free the electrodes for longitudinal adjustment. The outer holder 27 and electrode 14E are preferably arranged at right angles to the bar 11 which permits the operator to use the device in a corner.

Having thus described the invention, what is claimed as desired to be secured by Letters Patent is:

1. In an electric welding torch, in combination, a handle, a conducting bar secured in said handle, a second conducting bar slidably mounted in said handle in parallel relation to said first bar, means on the outer end of each of said bars for supporting an electrode, a coiled spring mounted in said handle and arranged to move said slidable bar inwardly of the handle, means for moving said slidable bar outwardly of the handle to move the electrodes toward each other, said means comprising a bell-crank lever pivotally mounted on said handle, and having one end thereof operatively connected to said slidable bar, the other end of said lever being located adjacent one side of said handle and in convenient position for manipulation by the hand of an operator grasping said handle.

2. In an electric welding torch, in combination, a handle having two substantially parallel passages extending longitudinally therethrough, a conducting bar secured in one of said passages and extending outwardly beyond one end of the handle, a second conducting bar slidably mounted in the other passage, a coiled spring mounted in said last named passage and surrounding said slidable bar and arranged to force said bar inwardly of the handle, means on the outer end of each of said bars for supporting an electrode, means for moving said slidable bar outwardly to bring said electrodes into operative position, said last named means comprising a bell-crank lever pivotally mounted on said handle, and having one end thereof operatively connected to said slidable bar, the outer end of said lever being located adjacent one side of said handle and in convenient position for manipulation by the hand of an operator grasping said handle.

3. In an electric welding torch, in combination, a handle, a conducting bar rigidly secured in said handle and extending beyond one end thereof, a second conducting bar slidably mounted in said handle and also extending beyond the end thereof, means on the outer end of each bar for supporting an electrode, a coiled spring mounted in said handle and surrounding said slidable bar and arranged to force said last named bar inwardly of the handle, a bell-crank lever mounted on said handle and having one end thereof operatively connected to said slidable

5 bar for moving the same outwardly against the action of said spring, the other end of said lever being positioned adjacent one side of said handle and forming means by which said lever may be manipulated by the hand of an operator grasping said handle.

4. In an electric welding torch, in combination, a handle, a conducting bar rigidly secured in said handle and extending beyond one end thereof, a second conducting bar slidably mounted in said handle and also extending beyond the end thereof in parallel relation to said first named bar, means on the outer end of each of said bars for supporting an electrode, a coiled spring mounted in said handle and surrounding said slidable bar and arranged to force the same inwardly of the handle, a bell-crank lever mounted on said handle, a thrust rod operatively connected to one end of said lever and to said slid- 10 able bar for moving the latter outwardly against the action of said spring, the other end of said lever being positioned adjacent one side of said handle and forming means by which said lever may be manipulated by the hand of an operator grasping said handle.

20 5. In an electric welding torch, in combination, a handle, a conducting bar secured therein and extending beyond one end thereof, a second conducting bar slidably mounted in said handle also extending beyond said end of the handle in parallel relation to said first named bar, said movable bar having an arm projecting laterally therefrom, means on the outer end of each of said bars for supporting an electrode, a coiled spring mounted in said handle and surrounding said slidable bar and arranged to move the same inwardly of the handle, a bell-crank lever pivotally mounted on said handle, a threaded thrust rod connected to one end of said lever and extending through said arm, an adjustable nut threaded on said rod for engaging said arm, whereby the position of said slidable bar and its electrode may be adjusted, the other end of said bell-crank lever being positioned adjacent one side of said handle and forming means by which said lever may be manipulated by the hand of an operator grasping said handle.

40 6. In an electric welding torch, in combination, a handle having two substantially parallel 50 passages extending longitudinally therethrough, a conducting bar secured in one of said passages and extending outwardly beyond one end of the handle, a second conducting bar slidably mounted in the other passage, a coiled spring 55 mounted in said last named passage and surrounding said slidable bar and arranged to force said bar inwardly of the handle, means on the outer end of each of said bars for supporting an electrode, and manually operable means 60 mounted on said handle for moving said slidable bar outwardly relative to the other bar.

CLARENCE IVENS BARCLIFT.
